UNITED STATES PATENT OFFICE.

JOHN H. VOGT, JR., OF COLUMBUS, OHIO.

TUBE SETTING AND SPREADING TOOL.

1,425,426.

Specification of Letters Patent. Patented Aug. 8, 1922.

Application filed February 7, 1921. Serial No. 442,960.

To all whom it may concern:

Be it known that I, JOHN H. VOGT, Jr., a citizen of the United States, residing at Columbus, in the county of Franklin and State 5 of Ohio, have invented certain new and useful Improvements in Tube Setting and Spreading Tools, of which the following is a specification.

This invention relates to an improved setting and spreading tool adapted for use in connection with the tubes of steam generating boilers for the purpose of enabling the longitudinal ends of such tubes to be readily and easily set and spread in connection 15 with a boiler sheet or head, in order that by subsequent operations the said ends of the tubes may be beaded or bent outwardly into fastened relationship with the sheet or head.

A boiler setting or spreading tool of the 20 type disclosed in this application, as is well known, usually consists of a plurality of concentrically disposed separable sections, which are normally held together by an elastic ring so that the sections will be capable 25 of relative expansion and yet will be held together, the said sections, when in their assembled form being formed with grooves which jointly produce a tapered longitudinally extending axial bore in the tool, the 30 latter being disposed for the reception of a tapered expanding plug, which by being driven into the bore will cause the sections to expand so as to effect an increase in the diameter of the tool, the arrangement being 35 such that when the tool is inserted in one end of a boiler tube, expanding the tool will result in producing corresponding expansion or spreading of the end of the tube, so that the latter, by having its end thus 40 expanded will be securely mounted within a boiler sheet or head and be capable of being further operated upon to produce an annular bead or ring which will permanently hold the tube in connection with the boiler 45 head or sheet.

In tools of this character it frequently occurs that when the plug is being driven into the bore of the tool so as to effect the expansion of the end of the tube, the latter, by 50 reason of the blows delivered to the plug, will be forced rearwardly or longitudinally so that the end thereof which should project a slight distance beyond the boiler sheet will be forced inwardly to such extent that the 55 end of the tube will be either forced within the confines of the boiler sheet or an insuffi-

cient length of the tube will project beyond the sheet to permit of the proper subsequent beading operation. This results in causing loss of time to effect the resetting of the 60 tube or else a considerable degree of skill is required on the part of the operator to avoid such longitudinal displacement of the tube during the setting operation.

In accordance with the present invention a 65 boiler setting and spreading tool is provided wherein the separable sections are formed to include longitudinally disposed spacing projections which extend parallel with the longitudinal axis of a tube to be spread and are 70 disposed beyond the confines of the end of the tube and disposed to engage the exterior surface of the boiler sheet or head when the tool is in active operation, the arrangement of the projections being such that when sections 75 are being expanded by blows delivered longitudinally to the expanding plug, longitudinal movement on the part of the tool as well as the tube itself will be precluded by the engagement of the projections or lugs with 80 the stationary boiler head or sheet, the tool thus admitting of the lateral or radial spreading of the end of a tube without accompanying longitudinal movement thereof and corresponding loss of relative adjust- 85 ment with respect to the boiler head, a feature which insures the proper setting of the tube, the requisite spreading of the end thereof and a sufficient amount of metal at the end of the tube, when the latter is finally 90 spread, to permit of the formation of an efficient and properly produced bead on the end of the tube, which will hold the latter in secured relation with the boiler head or sheet without permitting of longitudinal displace- 95 ment.

Other objects of the invention reside in a tool of this nature which will be simple and convenient in operation, capable of permitting the operations to be effected thereby to 100 be quickly and accurately performed and to provide a tool of compact and well balanced formation which will be capable of imparting extended service with but a minimum of repair and adjustment.

With these and other objects in view, as will appear as the description proceeds, the invention accordingly consists in the novel features of construction, combinations of elements and arrangements of parts, herein- 110 after to be fully described and pointed out in the appended claim.

In the accompanying drawing, forming a part of this specification, and in which similar characters of reference denote like and corresponding parts throughout the several views thereof:

Figure 1 is a side elevation of the improved tube setting and spreading tool comprising the present invention.

Figure 2 is a vertical longitudinal sectional view taken through the tool and illustrating the use thereof in connection with the setting and spreading of a boiler tube,

Figure 3 is an end elevation of the tool, and

Figure 4 is a detail perspective view of one of the separable sections thereof, and disclosing more particularly the construction of the holding projection.

Referring more particularly to the details of the invention, use is made of a boiler setting and spreading tool 1, which is formed to include a plurality of interfitting, relatively movable, separable sections 2. In cross section, these sections are substantially wedge shaped and have their adjacent faces disposed on true radial lines with respect to the center of the tool, in order that when the sections are operatively combined the tool as a whole will be of substantially circular formation when viewed in an elevation. To hold the sections in proper relation each thereof is formed to include a relatively enlarged body portion 3 having a segmental groove 4 provided in the outer circumference thereof, which groove will be capable of registering with the similar grooves of the remaining sections, in order that an annular groove will be produced when the sections are assembled to receive an annular elastic ring 5, of rubber or the like, the said rings serving to exert sufficient tension upon the several sections so as to draw the latter together and to maintain the same in proper operative relation. When the sections are combined in this manner the same will provide a longitudinally extending, axially located, inwardly tapering opening 6 in the center of the tool, which will be capable of receiving a tapering plug member 7, the latter being so formed that when driven into the opening 6, the said member will force the sections to be radially expanded, against the tension of the ring 5, so that the tool as a whole may be circumferentially expanded or contracted. The body portion 3 of each section terminates inwardly in a longitudinally extending finger 8, which cooperates with similar fingers provided upon the remaining sections to produce a reduced expandable sleeve upon the inner end of the tool, the said sleeve being relatively smaller in diameter than the body of the tool, and has the outer circumferential wall thereof tapered to correspond substantially with the taper of the plug member 7.

65 This sleeve is adapted to be received, when

the tool is in operation, within the open end portion of a tube 9, of the type commonly found in connection with boilers or other steam generating apparatus. As previously stated, the tool 1 is employed for the purpose of enabling the outer ends 10 of tubes of this nature to be properly set and expanded in secured relationship with respect to a boiler sheet or head 11, whereby longitudinal movement on the part of the tube 75 with respect to the sheet or head 11 will be precluded. In the past it has been customary to form the tool 1 to include the construction so far specifically described, and to insert the same into the end of a 80 tube which has been positioned within a receiving opening 12 therefor provided in the boiler sheet. Then, by driving the plug member 7 into the tapered opening 6 of the tool, it will be apparent that the sections of the 85 tool will be circumferentially expanded, and likewise a sleeve produced by the fingers 8, so that the end 10 of the tube will be spread slightly and thus wedged, as it were, into secured relation with the boiler sheet. However, it has been found in operation that when the tool 1 is so constructed, the application of power to the plug member 7 has frequently resulted in driving the tube 9 longitudinally to a more or less extent 95 during the setting and spreading operation, and this has frequently resulted in causing the end 10 to be forced into the opening 12, or to permit an insufficient amount of the tube 9 to project beyond the exterior surface of the sheet 11 to permit of the proper formation of a bead on the end of a tube. Therefore, to obviate this difficulty, the tool 1 has certain of its sections provided with longitudinally extending integral projections or lugs 13, which are formed to project from the inner side of the body 3 in spaced relationship from the exterior surface of the fingers 8, in order that by being so formed, the ends of the lugs or projections 13 will be capable of engaging with the exterior surface of the sheet 11, and yet will enable the ends 10 of the tubes 9 to be properly positioned and without suffering interference in any way from the projections or the body of the tool. It will be manifest that by the provision of the elements 13, the plug member 7 may be driven tightly and forcibly into the opening 6 so as to effect the desired expansion of the end 110 of a boiler tube, and yet the percussive force applied to the plug member in a longitudinal direction will only result in spreading the end of a boiler tube and will not in any way result in relative longitudinal movement of said tube with respect to the boiler sheet. Therefore, the end of a tube may be effectively and quickly expanded by use of the tool comprising the present invention and in such manner that a sufficient por- 115 120 125 130

tion of the tube will project beyond the outer surface of the sheet 11 for the purpose of permitting of the subsequent bead-ing of the end of the tube after the spreading operation has been performed. This end, as will be apparent, is primarily ac-complished by preventing longitudinal movement on the part of the tool itself during the spreading operation, and the tool 10 will enable the operation to be readily car-ried out in an expeditious, efficient and labor-saving manner. By forming the lugs 13 upon alternate sections, the desired sta-bility will be imparted to the tool and yet 15 the work may be viewed through the spaces provided between the lugs.

What is claimed is:

In a tube setting and spreading tool for boilers, a plurality of interfitting, circularly 20 arranged separable sections, formed to in-clude when assembled a relatively enlarged circular head and a reduced longitudinally extending expansible sleeve, said sleeve be-ing disposed to be received within the open

end of a boiler tube and upon being ex-panded to spread the end of said tube into holding relation with a boiler sheet, means 25 surrounding the head of said tool for main-taining said sections in assembled relation, the said tool being provided with a longi-tudinally extending tapering opening capa-ble of receiving a tapering expansion mem-ber, whereby upon the movement of said ex-pansion member longitudinally and in-wardly of the tool the circumference of said 30 sleeve will be expanded, and a plurality of pro-jections extending longitudinally from said head and provided upon alternate sec-tions, the said projections being disposed 35 to extend parallel to the longitudinal axis 40 of the tool and to engage with the outer surface of the boiler sheet, whereby upon the expansion of the sections longitudinal movement on the part of a tube will be precluded.

In testimony whereof I affix my signa-ture.

JOHN H. VOGT, JR.
